UNITED STATES PATENT OFFICE.

JAMES W. WILSON, OF MCKEESPORT, PENNSYLVANIA.

GAS-BURNER AND REGULATING-VALVE FOR BOILERS.

No. 796,274

Specification of Letters Patent.

Patented Aug. 1, 1905.

Application filed January 11, 1904. Serial No. 188,580.

To all whom it may concern:

Be it known that I, JAMES W. WILSON, a resident of McKeesport, in the county of Allegheny and State of Pennsylvania, have invented a new and useful Improvement in Gas-Burners and Regulating-Valves for Boilers; and I do hereby declare the following to be a full, clear, and exact description thereof.

My invention relates to a gas-burner and regulating-valve for steam-boiler furnaces; and one of the objects is to so arrange the gas-burners, supply-pipes, and regulating-valve as not to interfere with the coal-firing of the furnace.

Another object is to so construct and arrange the burners and regulating-valve that the burners need not be moved, and hence can be made as large as required and so as to avoid leakage of gas.

Prior arrangements for gas-firing of steam-boiler furnaces are such that they interfere with coal-firing, thus making it almost impossible to keep up steam if the gas-supply is shut off.

The object of my invention is to provide an arrangement for the gas-firing of steam-boiler furnaces wherein the above objections are overcome.

To this end it consists in providing a supply-pipe having the burners fixedly secured thereto and projecting into the combustion-chamber above the tops of the ordinary firing-doors and regulating the gas-supply by means of a suitable valve connected to the supply-pipe.

The invention also consists in a regulating-valve for this purpose so constructed that the seat and valve part can be easily removed and replaced and so that the dust in the gas is collected and easily removed from the gas-main.

The invention also consists in details of construction which will be hereinafter described and claimed.

In the accompanying drawings, Figure 1 is a front elevation of boilers equipped with my invention. Fig. 2 is a vertical section through the same on the line 2 2, Fig. 1; and Fig. 3 is a similar section on the line 3 3, Fig. 1.

My invention may be applied to any known form of steam-boiler, and in the drawings it has been shown applied to a well-known type of water-tube boiler, the drawings, however, showing only a portion thereof, the tubes be-

ing indicated at 1, the headers at 2, and the drum at 3. These will all be mounted, as is the custom, and inclosed in a suitable chamber. The combustion-chamber is shown at 4, and this may be of any known shape and construction of such chambers or it may be omitted entirely. It is provided with the grate 5 for burning coal and similar fuel and firing-doors 6 for supplying such fuel. Above the firing-doors are openings 7, through which project the gas-burners 8. The latter are shown as broad flat pipes curved so as to lead from an overhead supply-pipe 9 down and into the openings 7 of the combustion-chamber. These burners are rigidly secured to the supply-pipe 9, thus avoiding any sliding joints and the danger of leakage.

The supply-pipe 9 is suitably supported overhead so as not to interfere with the coal-stoking of the furnace. The regulating means are all placed at the side of the boilers, so as to leave a clear space in front of the same for coal-stoking. As shown in the drawings, each end of the supply-pipe 9 is connected to a valve-chamber 10. The valve-chamber 10 is comprised in a casing having an outlet-opening in one side wall communicating with the supply-pipe 9 and a supply-opening in its top communicating with the branch main 12 and regulated by a suitable valve. The branch main 12 leads to the supply-main 13. All of these parts are arranged overhead, so as to be out of the way of the stokers.

The valve consists of a bell 15, seating on an overhead seat 16 and arranged to open by moving downwardly. Any suitable operating means for this valve may be used, and in the drawings there is shown a rod 17, connected to the bell and extending through a stuffing-box in the gas-main, the upper end of this rod being connected to a lever 18, having thereon a counterweight 19 and a regulating-rod 19^a. Any other suitable means, however, might be employed.

The valve-seat 16 is clamped between a flange 20^a on the lower portion of the supply-main and a flange 20 on the upper portion of the valve-casing 10, so that said seat can be removed and changed from the outside without disturbing the valve-chamber. The bell 15 is also adapted to be readily removed, and to this end the valve-chamber is provided on one side with a door 21 of sufficient size

to enable the bell to be removed and changed. The valve-chamber is made sufficiently large so that when the valve is opened the gas will have ample room to pass. A damper or valve 23 will be provided in the branch main 12, so that the gas may be shut off while the valve or valve-seat is being changed.

When the regulating-valve is closed, the dust which always is found in gas will accumulate above the valve, and when the valve is open this dust will fall down into the valve-chamber. I make provision for removing the same. Underneath the valve-chamber is the dust-catcher 24, which consists of a suitable chamber closed at its lower end by any suitable valve, such as the bell 25. The supply-pipe 9, leading to the burners 8, projects from the side of the valve-chamber, and as a consequence the dust which accumulates on the bell 15 will when the latter is opened drop down into the dust-catcher 24 instead of being carried into the supply-pipe 9. The dust which is carried by the gas will also have a tendency to settle down into this dust-chamber, from which it can be periodically removed by means of the valve 25.

My gas supply and regulating arrangement is such that a clear space is left in front of the boiler-furnace, thus not interfering with the stoking of the furnace with coal. Furthermore, the burners 8 are immovable, so that no sliding joints are present, and leakage is thus avoided, the regulation of the gas-supply being accomplished by the valve in the supply-pipe instead of by removing the burners, as heretofore. This regulating-valve, furthermore, is so constructed that it can be readily changed, and provision is also made for clearing the gas of dust.

What I claim is—

1. A gas-burning steam-boiler furnace comprising a combustion-chamber, an overhead supply-pipe, burners connected thereto and projecting into the combustion-chamber, a valve in said supply-pipe at one side of the boiler-furnace and serving to regulate the flow of gas to the burners, and a dust-collection chamber underneath said valve and provided at its bottom with an opening for removal of the dust.

2. A boiler-furnace comprising a combustion-chamber, gas-burners projecting into the same, a supply-pipe connected to the burners, a valve-chamber having an opening in its side to which said supply-pipe is connected, a downwardly-opening valve in said valve-chamber, and a dust-collecting chamber connected to the lower part of the valve-chamber and located below the opening leading to the supply-pipe and provided at its bottom with a cleaning-opening.

3. A steam-boiler furnace comprising a combustion-chamber, an overhead gas-supply pipe, burners connected to said pipe and pro-

jecting into the furnace-chamber, a valve-chamber located at one side of the boiler-furnace and having an opening in its side communicating with the supply-pipe and having an inlet-opening through its top, a downwardly-opening bell for regulating said inlet-opening, and a dust-collecting chamber connected to the lower part of the valve-chamber and provided with a cleaning-opening.

4. A steam-boiler furnace comprising a combustion-chamber, an overhead gas-supply pipe, burners connected to said pipe and projecting into the furnace-chamber, a valve-chamber located at one side of the boiler-furnace and having an opening in its side communicating with the supply-pipe, a regulating-valve in said valve-chamber, a dust-collecting chamber connected to the lower part of the valve-chamber and located below the opening communicating with the supply-pipe, and a valve-controlled cleaning-opening in the bottom of said dust-collecting chamber.

5. A steam-boiler furnace comprising a combustion-chamber, burners projecting into the same, a gas-supply pipe connected to said burners, a valve-chamber in said supply-pipe, a valve-seat in said chamber, a downwardly-opening bell co-operating with said valve-seat, a door in the side of said valve-chamber to permit the removal of said bell, and a dust-collecting chamber connected to the lower part of the valve-chamber and provided with a cleaning-opening.

6. A steam-boiler furnace comprising a combustion-chamber, burners projecting into the same, a supply-pipe connected to said burners, a valve-casing having an opening in its side communicating with the supply-pipe and having a gas-inlet through its top, a downwardly-opening bell for regulating said inlet, a door in the side of the valve-casing to permit the removal of said bell, a dust-collecting chamber connected to the lower part of said valve-chamber and located below the opening communicating with the supply-pipe and provided with a cleaning-opening in its lower end, and means for closing said opening.

7. A steam-boiler furnace comprising a combustion-chamber, a grate therein, a firing-door above said grate, an overhead gas-supply pipe, burners connected thereto and projecting into the combustion-chamber above the top of the door, a regulating-valve in said supply-pipe at one side of the boiler-furnace, a dust-collecting chamber underneath said valve, and a cleaning-opening in the bottom of said dust-collecting chamber.

8. A steam-boiler furnace comprising a combustion-chamber, a grate therein, a firing-door above the grate, an overhead gas-supply pipe, burners connected thereto and projecting into the combustion-chamber above the top of the firing-door, a valve-casing at one side of the boiler-furnace and provided with

an opening in its side to which said supply-pipe is connected, a gas-regulating valve in said valve-casing, and a dust-collecting chamber connected to the lower part of the valve-casing and located below the opening leading to the supply-pipe and having a cleaning-opening in its bottom.

In testimony whereof I, the said JAMES W. WILSON, have hereunto set my hand.

JAMES W. WILSON.
